Geneva, Ill.

Application February 4, 1935, Serial No. 4,862

4 Claims. (Cl. 2-3)

The present invention relates to hats and more particularly to hats made of fibrous material.

Among the objects of the invention are to provide a novel hat composed of fibrous material and having a covering of suitable material and also a novel method of producing such hat. The invention comprehends the making of a hat which will be light in weight, which will have excellent heat transfer insulating properties, which will not absorb and hold fluids and thus will be fluid proof, which is impervious to fluids, which may be easily cleaned with the usual cleaning agents without any injurious effect on the hat, which is stiff, tough and durable, which may be colored and decorated as desired, which has coverings of any desired material, which will maintain its shape, which will have the appearance of hats made of cloth or the like, which may be produced quickly with simple operations at small expense and cost and on a large scale or in a large capacity of production without the necessity of making hats of different sizes to fit different sizes of heads thus eliminating the need for different equipment, machinery and apparatus for different sizes of hats, which will be accurately and uniformly made, which in the manufacturing thereof may be easily and quickly made in any desired shape or form, which may be compressed or compacted as desired, which will have sharp, well defined and distinct features, ornate or otherwise, which will have any surface finish desired and any color or combination of colors as desired, and which will have an attractive appearance.

The invention also comprehends the producing of a novel hat composed of fibrous material initially deposited, accreted, interlaced and integrated so as to form a seamless integral stiff hat in the final desired shape, form or contour and character, free of internal stresses tending to change its form, shape or contour as initially produced, thus avoiding warping, distortions and the like. The hat of the present invention is made or composed initially in its final and intended form of fibrous material deposited, accreted, interlaced, molded and integrated preferably upon a contoured porous former so that the member so produced is seamless, of the desired thickness and compactness or density, light in weight, stiff, tough and durable, and without deforming stresses and strains. There is no tendency for it to change to any other shape or contour or even become distorted to any degree, because it is not deformed from any other shape or contour, and hence it remains normally of the

shape it initially received when molded or accreted etc. Should anything tend to change its shape, it will restore itself to its original shape or state, thus making for permanency of form and condition.

Another advantage of making the hat by accreting fibrous material upon a contoured porous former is that any desired shape, contour and design feature may be obtained which would be impossible to effect by the deformation of a sheet of material, the final desired form being produced by the present invention initially when the fibres are accreted, interlaced and integrated.

Our invention comprehends more particularly the making of hats of the character described above with a covering, preferably of cloth, on either the outer or inner surface of the hat or both, said covering being preferably obtained by molding a sheet of cloth by means of dies of the same contour as that of the hat body blank, and maintaining said sheet under constant yieldable stretching tension in all directions throughout the molding stage, and until said sheet is caused to conform to the shape of the mold. The covering thus formed is continuous in all directions, that is, the strands are uncut from edge to edge, and the covering conforms in size and shape with the body and is free of tension and stresses in all directions. In the case of a cloth covering only on the outer surface of the hat, the latter preferably has an inner coating of any desired suitable substance with or without an inner liner of cloth or the like. In the case of covering both the outer and inner surfaces, the hat body or carcass is completely encased or enveloped in the cloth or like covering.

The body or carcass of the hat of the present invention is preferably produced by the method and means disclosed in the co-pending application of Jesse B. Hawley, identified as Serial No. 4,866, filed February 4, 1935, and as disclosed therein.

Other objects, advantages, capabilities, features, process steps and the like are comprehended by the invention as will later appear and as are inherently possessed by the invention.

Referring to the drawings;

Fig. 1 is a vertical sectional view through a means for forming the hat of fibrous material;

Fig. 2 is a similar fragmentary view of a form of drying die that may be used;

Fig. 3 is a view similar to Fig. 2 of the male drying die with a female drying die;

Fig. 4 is a vertical sectional view of a heat

transfer die means which may be used in lieu of the dies shown in Figs. 2 and 3;

Fig. 5 is a fragmentary top plan view of a part of the die means shown in Fig. 4.

5 Fig. 6 is a horizontal sectional view taken in planes represented by line 6—6 in Fig. 4 of the drawings;

10 Fig. 7 is a fragmentary vertical sectional view of a hat blank made in accordance with the invention;

15 Fig. 8 is a similar view showing a hat blank having coatings or coverings.

Fig. 9 is a similar view of a male die composed of yieldable material, such as rubber, gelatin or 20 the like;

Fig. 10 is a plan view of a holder for the cloth covering to be applied to the hat blank;

25 Fig. 11 is a vertical sectional view of a male die of yieldable material and showing a stretched sheet of cloth on it before the application of the female forming die;

Fig. 12 is a fragmentary similar view showing the application of the hot female die;

25 Fig. 13 and 13^a are similar views but showing another male die of yieldable material and a hot female die for treatment of the hat blank with its coverings;

30 Fig. 14 is a fragmentary sectional view taken through the edge or rim portion of the hat blank and its coatings and coverings prior to forming a bead;

35 Fig. 15 is a fragmentary vertical sectional view of part of a bead forming die means with a hat blank and its coverings in place before forming the bead;

Fig. 16 is a similar view showing the formed bead;

40 Fig. 17 is a fragmentary sectional view of a hat having an inner coating or covering of desired material as powdered cork or the like;

Fig. 18 is a similar view of a male die of yieldable material and a cloth liner for the brim portion of the hat before application of the liner to the hat blank;

45 Fig. 19 is a similar view showing the application of the liner and the use of a hot female die;

Fig. 20 is a similar view of the edge of the brim before beading;

50 Fig. 21 is a similar view showing the bead and the bead forming means, as in Fig. 16;

Fig. 22 is a view in elevation of a completed hat constructed in accordance with the invention;

55 Fig. 23 is a bottom plane view of the same; and,

Fig. 24 is a fragmentary sectional view on an enlarged scale showing a means of connecting the sweat band to the hat.

60 Referring more in detail to the drawings, the hat is produced from fibrous material, such as pulp or the like, and may include any other fibrous material such as wool, cotton, linen, silk, jute, hemp, asbestos, kapok, and similar fibrous material, the term pulp being herein used generically to include any, or any combination, of 65 the various fibres that may be used. For the purpose of carrying out the invention, the fibrous material is placed with water in a beater or beater engine to beat the fibres and to disintegrate and disperse the water, and also to shorten 70 and hydrate the fibres to the desired point or extent.

75 The mixture of batch as it is usually called is then treated with suitable substances to "proof" the fibres. This may be effected in any of several ways. As for example, while continuing the

beating of the material in the beater engine, water proofing wax or wax emulsion may be added to the mixture, as in the proportion of about 0.25 to 8 percent of the weight of the dry material first placed in the beater. The beating 5 and stirring may be continued for a sufficient period of time, such as from 10 to 15 minutes until the wax or wax emulsion has been thoroughly dispersed and mixed or incorporated with the fibres, after which powdered alum or a solution of alum may be added in a quantity sufficient to set the wax on or in the fibres. This wax or wax emulsion has the property of softening, and water and moisture proofing the fibres, as also smoothing the surfaces of the fibres. The 10 beating and stirring may continue until the setting has been effected, and then the material termed "stock" may be stored in a suitable tank or vat for use when molding or accreting on the porous former or die. 15

20 As other examples, in lieu of wax or wax emulsion, paper maker's rosin in an amount of about 1 to 5 percent of the weight of the dry material first placed in the beater may be used, or latex, or powdered or emulsified asphalt, and the like may be used, each of which may also be set with alum as above described in connection with wax. The rosin has the property of stiffening, and water and moisture proofing the fibres. The latex toughens and renders the fibres resilient or 30 resistant to deformation and the like. The asphalt is used to give the fibres water and moisture proofing characteristics as also for stiffening the fibres.

35 As further examples, proofing may likewise, by a like or similar process, be effected with starch, glue, casein, or silicate of soda, and the like, in which case setting with alum is not necessary as in the cases referred to above. The starch stiffens and smooths the fibres. The glue, 40 casein and the silicate of soda stiffens the fibres. The glue is particularly useful in connection with wax to counteract the softening effect the wax has on the fibres.

45 The fibrous material preferably used is that of pulp or pulp mixed with other fibres as desired. The pulp or pulp component may be of kraft fibres such as southern kraft fibres, sulphite pulp, or rope pulp, wherein the material is stiff and will produce a comparatively stiff hat. When using softer fibres such as soda pulp, the material is softer and produces a less stiff hat. The sulphite pulp reduces the shrinkage of the kraft pulp and adds strength when used with the soda pulp, and hence it is preferable to use sulphite 55 pulp especially the Mitscherlich pulp, with either the kraft or soda pulp. The unbleached fibres are stronger than the bleached fibres, while the Mitscherlich sulphite pulp is stronger than the common type of pulp fibres. Preferably the 60 kraft and sulphite pulp, both the common and the Mitscherlich type, are used. By mixing the stiffer with the softer materials with or without the other fibrous material mentioned above, any desired degree of stiffness or softness may be had. 65

70 The means selected to illustrate the invention comprises a molding or forming die in the form of a contoured plate 1 provided with a plurality of openings or apertures 2, the lower rim 3 of the plate being seated upon a table or platen 4 having an apertured hub 5 in which is secured the upper end of a duct 6 leading to a suitable source of suction or pressure (not shown). The platen 4 is adapted by suitable means (not shown) to be lowered into and raised out of the 75

bath 7 in a vat or tank 8. The plate 1 and the platen 4 enclose a chamber 9 in which is normally created a suction for the drawing of the water of the bath through the holes 2. The bath 7 consists of water and fibrous material the fibres of which are maintained in dispersed suspension in the water by suitable agitation of the bath by any desired means (not shown).

10 The upper and outer surface of the plate 1 is shaped or contoured to conform with the shape or form of hat to be molded thereon. Upon this contoured surface is a reticulated sheet or screen 10 of fine mesh and conforming in shape or contour to the surface contour of the plate 1.

15 In operation, with the device in the position shown in Fig. 1, a suction is created in the chamber 9, and the platen 4 with the plate 1 and screen 10 are lowered and submerged in the bath 7. The suction draws the water through the 20 interstices of the screen 10 and the holes 2 to be delivered to the duct 6, causing a deposit, accretion, interlacing and integration of the fibres in the form of a contoured layer or stratum 11 on the screen 10, the thickness and compactness or 25 density of this stratum depending upon the time of immersion, the magnitude of the suction, the nature of the fibres, and the percentage of fibres in the bath. In some cases setting up a vibration in the mold will also have some effect, particularly in the interlacing of the fibres.

When the desired layer or stratum is accreted, interlaced and integrated, the platen 4 and the mold die 1-10 with the fibrous material thereon are raised out of the bath. The suction during 35 emersion is continued to prevent the washing away of some of the fibrous material, and also, after emersion, to draw air through the fibrous blank or stratum for removing surplus water, that is, as a preliminary drying of the same. 40 If desired warm or heated air or the like may be thus drawn through the blank to dry the blank but it is preferable to dry the blank in a manner hereinafter disclosed.

To assist in expelling the surplus water in the blank, a female die 12 shown in dotted lines in Fig. 1 may be applied to the blank with pressure to squeeze out some of the water as also to partly compress or compact the blank, the suction in the chamber 9 continuing to draw out this water 50 and discharge it through the duct 6.

The female die 12 comprises a contoured wall or plate 13 conforming to the shape or contour of the blank, and having holes or apertures 14 for the passage of air. At the base is provided a base flange 15 upon which seats the lower edge portion 16 of the housing or casing 17 of the female die, this casing comprising walls 18 and a top 19, thus enclosing a chamber 20 about the wall 13. At a suitable low point is connected a 55 pipe or duct 21 for the discharge of any water that may be drawn through the apertures 14 under the influence of the vacuum created in the chamber 20 at the time when the wet blank 11 is compressed between the die walls 1 and 13.

60 The die 12 serves as a transfer means for the blank 11. After the blank 11 has been compressed, the vacuum in chamber 9 is discontinued and a pressure is effected therein while a suction is created in chamber 20 of the female die. The 65 die 12 is then lifted and the blank 11 will be lifted with it, the blank adhering to the wall 13 of the die 12. The die 12 with the blank 11 clinging to it are then brought over a hot male die 22 having a contoured wall or plate 23 provided with 70 a plurality of holes or apertures 24. The lower

portion of the wall 23 has a rim 25 which seats upon a table or platen 26 having an apertured hub 27 in which is connected a pipe or duct 28 leading to a suitable source of suction or pressure (not shown). The wall 23 and platen 26 thus enclose 5 a chamber 29. The die 12 and blank 11 are moved down so as to set the blank 11 on the contoured wall 23 as shown in Fig. 2, the die 12 applying the necessary pressure to compress and compact the fibrous material of the blank 11, and the 10 vacuum therein being changed to a pressure so as to relieve the blank from the die 12 and to cause it to adhere to the die 22, after which the die 12 is removed. The heat of the die wall 23 converts the moisture or water remaining in the 15 blank to steam, vapor and the like, which are drawn through the apertures 24 by reason of the vacuum in chamber 29 and are discharged through the duct 28. If desired heated or hot 20 air, gas, or other medium may be drawn through the blank and the holes 24 to effect a drying of the blank, but it is preferable to apply a hot female die 30 comprising an imperforate contoured wall or plate 31 the lower edge portion of which has a flange 32 upon which the lower edge 25 portion 33 of the housing or casing 34 seats. The casing 34 may be octagonal in shape and comprises end walls 35 and 36 (see Fig. 6), side walls 37 and 38, angle walls 39, 40, 41 and 42 provided with openings 43, 44, 45 and 46 for the projection 30 of flames from burners 47, 48, 49 and 50 into the chamber 51, and a top wall 52. Besides applying heat the wall 31 also applies pressure to compress and compact the fibrous material of the blank 11 as also to give the blank the desired finished definition of contour. The steam, vapor, moisture, and the like are drawn through the holes 24 and discharged through the duct 28.

If desired, and preferably, the drying and compressing may be effected on the heat transfer die 40 shown in Figs. 4, 5 and 6 wherein is shown a male die comprising a wall or plate 53 having at its lower edge a flange 54 seated upon a table or platen 55, thus enclosing a chamber 56 for containing a heat transfer medium. At the top the wall 53 45 has an opening 53a with which communicates a duct 57 preferably formed integral at its upper end to the plate 53 and having its lower open end 58 located in an aperture provided in the platen 55 (Fig. 4). The platen 55 is clamped to a platen 59 50 which has a opening 60 in line with the opening in platen 55 in which the duct portion 58 is located, and in which is connected an end of a duct 61 leading to a suitable source of suction (not shown). Both platens 55 and 59 are provided 55 with openings 62 and 63 for projection there-through of flames from burners 64 into the chamber 56.

In the upper or outer contoured surface of the wall 53 are provided a plurality of channels or 60 grooves 65, 66 and 67 extending more or less radially and of which channels 65 lead to and communicate with the opening 53a, there being also cross channels 68, 69, 70 and 71 more or less circular or oval shaped for establishing communications between and among the channels 65, 66 65 and 67 whereby steam, vapors etc. may be led to the opening 53a and duct 57.

Upon the wall 53 is located a contoured die wall 72 having a plurality of holes or apertures 73, 70 and being provided at its lower edge portion with a flange 74 seated upon the flange 54 of the wall 53. At the top the wall 72 has a boss 75 to conform with the top knot feature in the hat blank to be later more fully described.

5 The upper and outer contoured surface of the wall 72 is covered by a thin fine mesh reticulated member or screen 76 having the same contour as the wall 72, and having a base flange 77 seated upon the flange 74 of the wall 72 and an upper boss 78 conforming to the boss 75.

10 The hat blank 11 reposes on this screen having been transferred from the molding die shown in Fig. 1 by the transfer die 12 and placed upon the screen 76 by changing the vacuum in the chamber 20 of the transfer die 12 to a pressure, after which the transfer die is removed, and the female die 30 is brought in place to compress the blank 11.

15 The wall 31 of the female die 30 is contoured to the desired shape to be given to the hat blank, and has its base flange 32 above or over the flange 77 of the screen 76 and has at the top a boss 79. It will be noted that the die walls 72 and 31 as also the screen 76 have contoured design features, such as bosses 75, 79 and 78 to form a boss 80 in the blank 11 in representation of a top knot on the hat (Figs. 7, 8, 17 and 19), also ribs running radially over the crown part to form 20 ribs 81 in the hat blank in representation of seams or the like on the hat crown (Figs. 7, 8, 17 and 19), and also ridges 82, 83 and 84 to form ridges 85 in the hat blank in representation of folds or pleats 85 on the hat (Figs. 7, 8, 17 and 19).

25 30 While the female die compresses the blank 11, hot products of combustion are projected through the burner holes into the chambers 56 and 51 so as to heat the walls 53 and 31 and to supply heat to the wall 72 and to the blank 11. A suction is effective in the duct 57 whereby the steam, vapors, and moisture formed in the material of the blank will be drawn out by way of the reticulations of the screen 76, the holes 73 in the wall 72, the channels 65-71 in the surface 35 of the wall 53, and thence to the opening 53 and through the ducts 57 and 61. The blank is thus dried and set with the desired finish definition as impressed by the particular surface contour of the die walls and the screen 76. The female die 30 may then be removed and the blank taken off 40 of the screen 76. If desired a transfer die similar to that shown in Fig. 1 with a suction in its chamber may be used to remove the blank from the screen 76, after which a pressure in the chamber 45 of the transfer die will suffice to blow off the blank.

50 The hat blank or carcass shown in Fig. 7 is therefore substantially stiff, strong, tough, and water and moisture proof, the fibres from which it is composed having been treated in the beater with the "proofing" substances mentioned above. The stiffness of the blank is particularly of the kind whereas when a part of the hat is displaced or strained, it will either be readily restored to its 55 original form without any injury to the hat, or restore itself to its original shape when the straining stress is removed, a characteristic which is not present in articles accreted in the usual way from the usual fibres, the "proofing" 60 substances and the mode of "proofing" giving the hat, in this invention, the peculiarly new and beneficial properties and characteristics mentioned above. The moisture and water proofing quality is such as to make it unnecessary to coat 65 the hat with a coating or covering of water and moisture proofing substance, but in the present invention it is preferable to apply a coating either on the outside or inside surface or both which will form a covering or skin to seal off the 70 interstitial spaces or cells in the fibrous body of 75

the blank particularly for effecting insulation against heat transfer, although incidentally the coating will also add to the water and moisture proofing property or characteristic of the hat body.

5 After the blank, as shown in Fig. 7, has been dried and set, its rim portion 11^a is preferably dipped in shellac or the like so as to facilitate the later forming of this rim portion into a bead later described herein.

10 After the shellac has dried, it is preferable to coat, as by brushing, the outer surface of the blank with a "size" so as to form the coating or skin referred to above. If desired, particularly in the case of where the inside of the hat 15 is to have no cloth covering or to have only a cloth liner on the inside of the brim, a like coating may be applied on the inside surface of the hat. In the case of where both the inside and outside surfaces of the hat are to be wholly cloth 20 covered, it is preferable to omit the inner coating of the size. For the purpose of illustration the coatings are designated by the reference characters 86 and 87 in Fig. 8 of the drawings.

25 The "size" preferably used is that known as nitrocellulose cotton which is dissolved in lacquer solvents, and is preferably pigmented with any of the various enamel pigments suitable to the color the hat is to have, or any suitable dye may be incorporated for the same purpose. If desired 30 any other similar "size" may be used such as that made from acetate cotton. Even latex or rubber cement and the like may be used. The "size" does not penetrate the fibrous mass but simply forms a sealing coating or skin on the 35 surface of the blank. The coating or coatings, as the case may be, also increase the water proofing properties or characteristics of the hat material.

40 After the coating or coatings are dry, either the outside or both the outside and the inside may then be coated with a coating 88 and/or 88^a of a thermoplastic substance preferably of a resin base, or the like, the thermoplastic being 45 preferably applied by spraying in liquid form and having a volatile solvent. After the volatile solvent has evaporated and the thermoplastic substance has dried, a cloth covering is applied and a hot female die with the proper contoured wall is pressed against the cloth covering with requisite pressure. The heat of the female die causes 50 the thermoplastic substance to fuse or become sufficiently plastic as to become bonded to the cloth covering as is more fully explained later. Then the die is removed, the thermoplastic substance so setting as to bond the cloth to the hat thus forming a tough durable covering for the hat.

55 When applying the cloth covering, it is preferable to place the coated blank on a die 89 (Fig. 9) 60 of suitable yieldable material, such as rubber, gelatine and the like, the die being fixed to a platen 90 having a support 91.

65 The thermoplastic substance referred to is in the class of synthetic resinous compounds known as the vinyl resins of the polymerization group and more particularly those which are permanently thermoplastic, characterized by the bond group or radical —CH₂CH₂, and which are insoluble in most all known solvents, particularly 70 the hydrocarbon solvents, except the solvents of the ester type or the higher ketones, such as hexone and butyrene. In other words, the substance used in this invention is chemically inert to the extent indicated above and hence is im- 75

pervious to and proof against moisture, water, acids, alkalies, alcohols, oils, greases, fats, and the like. In its normally pure state it is odorless, tasteless, colorless, and transparent. It is also 5 non-inflammable. It may be given any color or made translucent or opaque as desired by the incorporating or mixing therewith of dyes, pigments, fillers, or the like. It is also tough, durable and resilient. It also has a very strong 10 bonding or adhesive property. It may be applied either in liquid or solid form or both. When using this substance in liquid form, acetone preferably is used as the solvent but it is to be understood other solvents as mentioned above may be 15 used without affecting the idea of invention herein disclosed.

The present invention comprehends the application of a covering of cloth or the like to the outer surface of the hat blank, or to both the 20 outer and inner surfaces of the hat blank, so as to produce a hat with a cloth or like covering, or whereby the hat blank or carcass will be entirely encased or enveloped in the cloth or like covering.

25 In either case of applying a cloth covering to the outer surface of the hat or to both the outer and inner surfaces, of the hat, each covering of cloth may first be formed or deformed between dies to the general shape of the hat blank before 30 applying the covering or coverings, although in some cases depending on the kind of cloth used, the covering may be applied directly to the blank without preforming the covering sheet.

Referring to Figs. 10, 11, 12 and 13, a sheet 92 35 of cloth is held in a stretched condition by a group of resilient connecting elements 93 such as springs suitably engaged with the cloth as by clips 94 and with a ring 95. The cloth is wetted with water or other suitable liquid and is then brought 40 over a male die 96 of yieldable material such as rubber, gelatin or the like, and is stretched taut over the die as shown in Fig. 11 by forcing down the ring 95 (shown in Fig. 10) around the die and below it. The die has on its contoured surface a 45 stratum 97 of fibrous material such as one of the uncoated hat blanks, the stratum 97 adhering to the surface of the die body 96 with any suitable adhesive not affected by water, steam, moisture and heat. To the outer surface of the stratum 97 50 is engaged a sheet 98 of cloth also made to adhere to the stratum with a suitable adhesive which is not affected by water, steam, moisture and heat, and which is also pervious so as to permit passage of steam, vapors, moisture and the like.

55 With the parts in the position as shown in Fig. 11, the cloth 92 being held in taut stretched condition, a hot female die 30^a having a contoured wall 31^a, such as shown in Fig. 12 of the drawings, is forced down over the assembly so as to change 60 the shape of the cloth sheet 92 to the contour of the die surface, that is, to conform to the contour of the surface of the cloth sheet 98, as clearly shown in Fig. 12. The threads of the cloth sheet 92 are so stressed and strained as to make the 65 sheet 92 attain the contoured form or shape shown in Fig. 12. The steam, vapors and moisture escape through the interstices of the strata 97 and 98 to the lower edge thereof. After the cloth sheet 92 is dried, the female die 30^a is re- 70 moved and the cloth sheet 92 peeled off of the die 96. The die 30^a is similar to that shown in Figs. 3 and 6 with the exception it is preferably heated by steam instead of by flames from burners, and hence has ducts 33^a for conducting steam into 75 and from the chamber 51^a of the die. The above

described method of molding the cover has a very decided and important advantage, which has been fully set forth in the copending application Serial No. 68,458, filed March 12, 1936, which is a division of this application, and further description 5 thereof is deemed unnecessary. It is sufficient to say at this point, however, that the tendency of the molded cover to change its shape after the molding operation, due to unequal strains and stresses upon the different threads of the fabric, 10 is practically prevented.

The cloth 92 is then placed on the hat blank which is on the male die 89 (see Figs. 9 and 13). As stated above the hat blank has on its outer surface a covering or stratum 87 of thermoplastic 15 substance. This stratum is of sufficient thickness as to penetrate the cloth piece 92 when subjected to heat as described below.

A hot female die, such as die 30^b with the contoured wall 31^b, is forced down over the cloth 92, 20 and the heat of the die causes the thermoplastic substance to fuse and become sufficiently plastic so that it penetrates into the cloth 92. This die is like die 30^a and is preferably steam heated, with the exception the wall 31^b has a finish surface 25 contour which is not present in die wall 31^a.

In the present invention the thermoplastic substance is preferably applied to the surface of the coated hat blank by spraying in liquid form, although it might be applied with a brush. As 30 the volatile solvent evaporates the liquid thickens and even becomes tacky. Air drying may be used but if desired the coating may be dried more quickly in heated air or the like. It is preferable to air dry first to obtain a removal of the major 35 portion of the volatile solvents, and then force dry, in heated air, to remove the residual volatiles.

As indicated above, the die 30^b is applied with pressure. It is heated to the necessary temperature to fuse and melt the thermoplastic substance 40 so that it will be sufficiently plastic or fluidal to flow under the influence of heat and pressure of the die. The fused thermoplastic substance will enter or penetrate into the interstices of the cloth 45 92 to unite therewith. The die is then removed and the thermoplastic substance will congeal or solidify and set. This substance acts as a stiffener or reinforcer for the body of the hat. It also acts as a very strong adhesive or bond for 50 maintaining the parts in the relations assumed when subjected to pressure and heat; also as a protecting and preserving means preventing the access of moisture and other deteriorating media, etc. to the material of the hat and the cloth covering, and also, in some cases, as an adorning or 55 embellishing means to give the hat an appearance of elegance and the like.

The above discloses the applying of an outer cloth covering for the hat. The same operation 60 is used for applying inner and outer coverings of cloth. Referring to Fig. 13^a, the cloth 90^a destined to form the inner covering of the hat is placed upon a die 89^a of suitable yieldable material such as rubber, gelatin and the like. A 65 rubber band 198 is preferably stretched over the lower portion of the cloth 90^a to hold it in place as shown in Fig. 13^a. Then the hat blank with its coatings or coverings of thermoplastic material 88 and 88^a, is placed upon the sheet 90^a of 70 cloth reposing on the die 89^a. Then the sheet 92 of cloth which is destined to form the outer covering of the hat is placed upon the outer surface of the hat blank as shown in Fig. 13^a. The 75 coverings 88 and 88^a of thermoplastic material 75

are of sufficient thickness as to enter or penetrate into the cloth coverings to become united thereto or bonded therewith when the assembly is subjected to heat and pressure as described 5 below.

A hot female die, such as die 30^b with the contoured wall 31^b, is then forced down over the outer sheet of cloth, and the heat and pressure of the die causes the thermoplastic substance to 10 so fuse or become plastic as to penetrate into and become united or bonded with the cloth coverings 90^a and 92. The die is then removed and the thermoplastic substance sets and solidifies. This substance acts as a stiffener or rein- 15 forcer for the body of the hat, also as a very strong adhesive or bond for firmly and rigidly maintaining the parts in the relations assumed when subjected to pressure and heat, also as a protecting and preserving means for preventing 20 the access of moisture and other deteriorating media, etc. to the material of the hat and the cloth coverings, and also in some cases, as an adorning or embellishing means to give the hat an appearance of elegance and the like.

25 After the die has been removed and the thermoplastic substance has set, the inner cloth sheet 90^a is trimmed even with the outer edge of the rim 11^a, and the outer sheet 92 in either case of making the hat with an outer cloth covering 30 or with outer and inner cloth coverings, is trimmed to leave an overhang 99 (see dotted line showing in Fig. 14). A coating or covering of thermoplastic substance 100 besides covering the inside of the hat also is applied to the edge 35 of the rim and to the inner surfaces of the overhang 99 and the edge portion of the rim of the cloth 90^a when the latter is present, in ample amount for bonding the parts when the overhang is turned or folded in over the edge of the rim. 40 The extension 99 is shown in dotted lines in Fig. 14 before it is turned or folded in and in full lines after it is turned or folded in, the extension then having a part 101 bonded to the edge of the blank, and an inwardly extending part 45 102 bonded to the inner marginal portion of the hat brim rim or the edge portion of the cloth 90^a as the case may be. An expansible band or hoop 103 may be used to hold the part 102 in place until the thermoplastic substance dries.

50 The beading die means is shown as comprising two die parts 104 and 104^a of which the die part 104 has a wall 105 contoured to correspond to the outer surface of the hat, this wall having a part 106 for supporting the brim part of the hat, and 55 a part 107 for supporting the crown of the hat. The lower portion of the wall may be open for the projection of the crown top as shown in Fig. 15. The wall 105 is preferably formed integral with a supporting base 108 which may be cylindrical or oval shaped. The upper outer edge 109 is designed to be no greater in diameter than the outer diameter of the hat brim, as is clearly shown in Figs. 15 and 16.

The die part 104^a comprises an annular plate 60 110 having upstanding spaced annular walls 111 and 112 forming therebetween an annular channel 113 with which communicate pipes or ducts 114, there being two pipes of this kind, one acting as an inlet and the other as an outlet, for 65 delivery and discharge of heat transfer media or fluids. The upper edges of the walls 111 and 112 seat against a cover plate 115 suitably secured to the walls 111 and 112 in fluid tight contact.

70 Depending from the plate 110 is a rim 116

having a chamfered part 117 which serves to guide the rim 116 over the edge portion of the hat. The rim has an inner smooth guide surface 118 leading into a bead forming or curling groove 119 provided in the plate 110 adjacent the rim 5 116, as clearly shown in Fig. 15 of the drawings.

To the cover plate 115 are threadedly secured posts 120 having heads 121 on which is normally supported a presser plate 122 having a contoured surface 123 to conform with the inner surface 10 of the brim of the hat when the die part 104^a is lowered for the presser plate to press on the brim of the hat to hold the hat in place when being acted upon. On the posts are springs 124 which react between the plates 115 and 122 as 15 is clear from the drawings.

To form the bead or to curl the rim portion, after removing the band 103, the upper die component 104^a is lowered, the inner smooth guiding surface 118 of which slides over and along the outer surface of the rim part of the hat. At the same time the presser plate 122 contacts the brim part of the hat at the surface 123 of the plate, the springs 124 being compressed to apply 20 the required pressure.

25 As the die part 104 is further lowered the upper edge of the rim of the hat is forced into the groove 119 at the outer side thereof and the edge portion of the rim is curved or curled inwardly as it is caused to move along the curved surface 30 of the groove so as to bring the end of the curl or the edge of the curled part into engagement with the inner face of the brim as is clearly shown in Figure 16 of the drawings. Steam or other heat transfer medium is passed through 35 the chamber 113 of the die part 104^a as the latter is held in place to hold the curled part or bead in the form shown in Fig. 16. The heat is transmitted through the bead body so as to fuse the thermoplastic substance whereby it will permeate 40 the coverings of the bead, especially the portion contacting the brim of the hat. Then cooling water or other heat exchange medium is passed through the chamber 113 to cool the die part 104^a. This causes the thermoplastic substance 45 to set and harden or congeal so as to rigidly and firmly hold the bead in its curled form and to firmly bind or unite the edge portion of the bead to the adjacent portion of the hat brim. The die part 104^a is then raised and the hat removed from 50 the die part 104. Whether or not the edge portion of the bead be bonded to the adjacent portion of the hat brim, the solidified thermoplastic nevertheless rigidly holds the bead to its curved shape.

55 In the case of a hat not having any inner cloth covering, it is preferable to apply colored thermoplastic substances to the inside of the hat, and hence the inner coating or covering of the thermoplastic material 100 (see Fig. 17) may be of 60 any desired color. As for example the portion of this covering which covers the brim part of the hat may be of a color such as green and the portion which covers the inside of the crown may be white or any other desired color. In 65 some cases it may be desired to coat the coated part in the crown with some substance like powdered cork. In Fig. 17 is shown a coating of powdered cork 125. This may be applied by brushing the inside of the crown with a clear "size" and then sifting fine powdered cork on this wet coating. After drying with the adhering cork the lacquer coating may be sprayed thereover. In 70 this way the insulating qualities of the hat may be increased or enhanced. After this treatment 75

the edge may be trimmed or be curled as previously described.

In some cases, it may be desired to place a liner on the inside of the brim of the hat. In such case, (Fig. 18) a liner of cloth 126, which may or may not have been previously treated on its outer surface with a thermoplastic substance, is placed upon the brim portion of a male die 127 of suitable yielding material such as rubber, gelatine 10 and the like. If desired, a coating of thermoplastic substance may be applied to the surface of the liner at this time, or preferably, a coating of thermoplastic substance is sprayed on the inner surface of the hat brim. The hat blank is then 15 placed upon this die and upon the liner so as to attain the relationship shown in Fig. 19. Then the hot female die 30b may be brought into place to apply heat and pressure so as to cause the liner 126 to adhere to the brim portion of the blank 20 and also to cause a fusion or melting of the thermoplastic substance whereby the liner 126 will be bonded to the brim portion of the blank. The die is then removed and as the thermoplastic substance solidifies and sets, the liner is firmly 25 held bonded to the brim of the hat. The edge portion of the blank is then treated in the curling die so as to form a bead as shown in Fig. 21. In this case, the edge portion 128 of the liner is trimmed even with the edge of the blank and the 30 overhanging portion or extension 98 of the outer cloth covering (see dotted line portions thereof in Fig. 20) is turned in or folded inwardly into the position shown in Fig. 20 and held in position by the ring or hoop 103 as in Fig. 14. The 35 curling of the edge is performed in the same way as described in connection with Figs. 14, 15 and 16 so as to provide the bead shown in Fig. 21.

The hat as formed in accordance with the present invention and following the illustrative 40 embodiment selected to illustrate the invention, comprises a crown 130, a brim 131 having an edge bead 127. At the top of the crown is formed a boss 80 to represent a top knot, ridges 81 to represent seams or the like, and ridges 85 to represent folds or pleats or the like.

At the juncture 132 between the crown and the brim and inside of the hat are located connecting means 133 which, in the particular embodiment selected to illustrate the invention, are shown in the form of resilient strips which may be metal 50 or the like. Each strip is provided at its lower end with an opening for receiving the shank of a lug or male part 134 of a glove snap type of securing or fastening means, the shank being 55 provided with suitable flanges 135 and 136 at both sides of the lower end of the member 133. A socket or female part 137 of the glove snap type of fastening means extends through a hole provided in the juncture 132 of the hat and has 60 an inner flange 138 abutting the inner surface of the hat and an outer head or flange part 139 of such a size as to form a sort of an abutting flange at the outer surface of the hat.

The upper end of the strip 133 has a bend 140 65 and a short suspending end portion 141 which is provided with a hole in which is received a hollow rivet or eyelet 142 suitably secured to the hat band 143 as clearly shown in Fig. 24.

The hat band 143 is in the form of a strip of 70 material which has sufficient stiffness to be held in some general form and still is resilient enough to give for changing the size of the band. In the drawings, this hat band is shown to be of oval shape and is connected at spaced points to the connecting or supporting strips 133 as clearly in-

dicated in the drawings. The band has free end portions 144 and 145 which may be suitably connected together by any suitable means. In the particular embodiment selected to illustrate the invention the end portions 144 and 145 are provided with eyelets 146 and 147 through which may be threaded a cord of elastic or non-elastic material as desired, in such manner that the ends 148 and 149 of the cord may be tied together to form a knot 150 at such a point as to determine the size of the hat band. By tying the cord with greater or less length of the lap of the cord between the end portions of the hat band, it will be apparent that the end portions 144 and 145 may be at a greater or less distance with respect 15 to each other accordingly increasing or decreasing the size of the hat band.

In making adjustments of the size of the hat band each element 133 is capable of swinging about the axes of the snap means and also of 20 the eyelet 142 to one side or the other. In other words, as the hat band is enlarged or made smaller in size the member 133 will be capable of movement angularly about either the axes of the snap or angularly about the axes of the eyelet 25 in the hat band. In this way, the resilient members 133 compensate for the adjustment or variation in the size of the hat band. There is sufficient friction between the flanges of the snap and the flanges of the eyelets on the hat band 30 as to hold the elements 133 in adjusted position.

The members 133 are also flexible so that as the hat band is forced upon the head, when placing the hat upon the head, and is expanded at the lower portion of the hat band, the members 35 133 will be flexed in compensation of that movement of the hat band.

The hat, it will be noted, is supported by way of the elements 133 in a sort of suspension from the hat band, the hat band being supported 40 on the head of the wearer. It will also be noted that the hat band is spaced from the lower portion of the crown so that there is provided an air space between the hat band and the hat so as to afford free circulation of air. By reason of the 45 resiliency or flexibility of the members or elements 133, when the hat band is placed upon the head, there is a certain amount of tension or pressure tending to hold the hat band snug yet comfortably upon the head of the wearer.

A chin strap 151 may also be secured to the hat band by suitable connecting elements, such as the lug and socket snap referred to above, such snap being designated as 152 and 153 in Fig. 23, it being understood that they are the 55 same type as shown in Fig. 24.

One of the advantages of having both the hat band and the chin strap detachably connected to the hat is that the hats may all be made of one size and when the hat is to be used by the wearer 60 of a different size of head, the hat band which is nearest to the size of the head may be easily snapped into place by snapping the male parts into the female parts of the snaps. If the hat band is not of the exact size of the head, adjustment may be made by tying the knot 150 at the proper point for the particular size of head of the wearer. Then the chin strap which has been chosen by the person to wear the hat, may be easily snapped into place as is obvious from the 65 drawings.

Another advantage is that should the hat be used by a person for a short period of time, such as by an Army man, the hat may then be issued to another Army man but a new hat band and 70 75

a new chin strap will be attached into place in lieu of the ones formerly used by the previous Army man. It will obviate the necessity of issuing an entirely new hat to the second man.

5 5 Another advantage is that when it is desired to clean the hat, it is an easy matter to remove the hat band and the chin strap and after the hat has been cleaned it is as easy to replace them.

While we have herein disclosed a few embodiments of the invention and a method of making the same, it is to be understood that the invention is not limited thereto but comprehends other constructions, details, arrangements of parts, features, process steps and the like without departing 10 15 16 17 18 19 20 21 22 23 24 25 26 27 28 29 30 31 32 33 34 35 from the spirit of the invention.

Having thus disclosed in the invention, we claim:

1. A hat comprising a body composed of compressed pulp material the fibers of which have been initially so accreted and compressed as to form a relatively thin substantially rigid integral unit of the desired form, a pre-formed covering complementary to the contour of said body and adhered to at least one surface thereof, said covering consisting of a single piece of woven fabric whose strands are uncut from edge to edge and conforming in size and shape with said body and free of tension and stress in all directions so as to maintain its contour independently of said body.

2. A hat comprising a body composed of compressed pulp material the fibers of which have been initially so accreted and compressed as to form a relatively thin substantially rigid integral unit of the desired form, a pre-formed covering complementary to the contour of said body and

adhered to at least one surface thereof, said covering consisting of a single piece of woven fabric whose strands are uncut from edge to edge and conforming in size and shape with said body and free of tension and stress in all directions so as to maintain its contour independently of said body, and said cover extended over and covering the edge of the brim of said body. 5

3. A hat comprising a body composed of compressed pulp material the fibers of which have been initially so accreted and compressed as to form a relatively thin substantially rigid integral unit of the desired form, a covering of woven material on at least one surface of said body and extending around the edge of the brim thereof, 10 15 a thermo-plastic material adhering said covering to said body, the edge portion of said brim rolled into a hollow bead with the covered edge thereof in abutment with the covered face of said brim, said thermo-plastic material adhering said edge 20 to said brim face.

4. A hat comprising a body composed of compressed pulp material, the fibers of which have been initially so accreted and compressed as to form a relatively thin substantially rigid integral 25 unit of the desired form, a covering of cloth on at least one surface of said body contributing to the stiffness thereof, a bonding substance firmly and intimately bonding said covering to said body, the edge portion of the brim and cover rolled 30 into a bead with the edge thereof in abutment with a surface of said brim, and bonding material adhering said edge to said brim surface.
